PUMP PISTON

James C. Francis, Jr., Fort Worth, Tex., assignor
to Superior Oil Tool Corporation, Dallas, Tex.,
a corporation of Texas

Application December 20, 1947, Serial No. 792,908

4 Claims. (Cl. 309—4)

1

This invention relates to pistons for slush pumps, and the like, of the type ordinarily employed in oil well drilling operations for pumping and circulating drilling fluids, and its principal object resides in the provision of a durable and economical piston in which is embodied certain novel features of construction by which the piston rubbers, of the cup type, can be quickly and easily installed at the job, resulting in great savings of time and labor costs.

Another object of the invention resides in the provision of a slush pump piston which is comprised primarily of metal for its supporting structure, yet providing an assembly which is capable of affording the maximum of efficiency in operation, effecting a minimum of wear on the cylinder liner while providing exceptional flexibility in performance to lighten the load and, at once, increase the volume of the pump in which it is installed.

Still another object of the invention resides in the provision of a piston structure having a body portion of durable metal to which the piston rubbers can be attached with economy and replaced, as the same are worn due to abrasive substances in the fluids handled by the pump, and providing a device in which a minimum amount of rubber, or other suitable composition, need be employed, resulting in longer life for the piston liner, less slippage in operation and greater economy in installation and replacement.

Broadly, the invention contemplates the provision of a slush pump piston which is light and economical in construction, highly efficient in operation and capable of being quickly installed with a minimum loss of time, and further contemplates the provision of a piston which is interchangeable with practically all of the standard brands of slush pumps now in use.

While the foregoing objects are paramount, other and lesser objects will become manifest as the description proceeds, taken in connection with the appended drawings wherein:

Figure 1 is a vertical cross-sectional view of the piston structure, illustrating the form of the body and the interlocking rubber cup, the assembly being shown attached to a tapered pump rod of conventional design.

Figure 2 is a lateral cross-sectional view of the piston, taken on lines 2—2 of Figure 1, illustrating the arrangement of integral interlocking lugs formed on the rubbers engageable with the piston body.

Figure 3 is a perspective illustration of the body of the piston, showing the plurality of staggeredly

arranged slots for receiving the interlocking lugs on the cup members, and

Figure 4 is an elevational view of the inner side of the rubber cup members, showing the staggered arrangement of integral lugs formed thereon providing interlocking association of the cup members with the piston body.

Accordingly, the invention comprises a main body portion 10 which is formed with a substantially cylindrical hub 11 whose inner bore 12 is preferably tapered, as in Figure 1, and thus adapted to be applied to the conventional tapered spindles of pump rods 13 which are generally deemed stronger and capable of longer life than rods having straight spindles. About the central hub 11 the body is formed with a hollow, drum-like structure 14, integral with the hub 11, and about its periphery is formed an integral flange 15 whose opposite faces *a* are tapered inwardly, as in Figure 1.

The opposite faces 16 of the hollow portion 14 of the body 10, are each formed with a plurality of staggeredly arranged arcuate slots 17 which extend through the walls of the member 14, as illustrated in Figures 1 and 3. It is desirable that the portion 14 of the body 10 have its opposite faces 16 at right angles to the axis of the hub 11. However, it is obvious that the faces 16 may be inclined either inwardly or outwardly, as desired, but the piston thrust can be better absorbed by the right angular arrangement of the faces 16 which support the cup rubbers 18, illustrated in Figures 1 and 4, fitted thereagainst.

The rubbers 18 are disk-like in form, as shown in Figure 4, and have annular flanges 19 formed thereon whose outer rims *b* are bevelled inwardly, as in Figure 1, conformable to the inwardly tapered faces *a* of the flange 15. The annular flanges 19 have their outer surfaces slightly inclined toward their tips *b* and, with a slightly bevelled annular surface 20 formed on the outer edges of their faces, the rubbers 18 are formed with peripheral lips 21 about their peripheries which are adapted to expand against the pump liner under pressure of the fluid.

The inner faces of the rubbers 18, as depicted in Figure 4, are formed with a staggered arrangement of integral, arcuately formed lugs 22 which are engageable with the arrangement of arcuate slots 17 in the face of the drum-like portion 14 of the body 10, as illustrated in Figure 1. Such an arrangement will prevent any rotative movement of the rubbers 18 on the body 10 and serve to provide a more rigid and compact structure for the entire piston assembly.

The rubbers 18 are retained upon the body 10 by retainer plates 23, which are disk-like in form, and secured by cap screws 24 extending through the rubbers 18 and threaded into the opposite faces 16 of the drum-like portion 14 of the body 10, as illustrated in Figure 1. The provision of the hollow space 24' within the portion 14 of the body 10 lightens the piston assembly and affords greater efficiency in the operation of the pump. The hub 11 of the body 10 is arranged over the tapered spindle 25 of the pump rod 13 and is secured by a nut 26 threaded upon the outer end of the spindle 25, in the conventional manner. A packing ring 27 is provided to effect a fluid-tight seal about the spindle 25 and reposes in an annular recess c in the end of the hub 11. The nut 26 bears against a washer 28 which retains the ring 27 in the manner shown in Figure 1.

The cup rubbers 18 are identical in form and are interchangeable so that either can be applied to the body 10 from either side thereof and such an arrangement provides for greater economy in stocking as well as handling the members 18. The body 10 may be formed by casting the same in any suitable metal, such as brass, steel, or the like, a minimum of machining being required to adapt the body 10 for installation and the attachment of the rubbers 18.

Manifestly, the structure herein shown and described is capable of considerable modification, from time to time, by persons skilled in the art, without departing from the spirit and intent of the invention or the scope of the appended claims.

What is claimed is:

1. In a piston for slush pumps, and the like, in combination with a plunger rod and pump liner, a cast body member having a hollow cylindrical, drum-like form, and an integral hub portion conformable to said plunger rod, the said body member having each of its opposing faces spaced inwardly from the ends of said hub portion and formed with a plurality of spaced slots, an integral flange formed intermediate the ends and about the periphery of said body member, a pair of flexible cup members interchangeably arranged over said body member and having integral bosses on their inner faces adapted to engage said slots, and retainer plates for said cup members.

2. In a slush pump piston, in combination with a pump rod and cylinder liner, a hollow body formed with a hub member conformable with said pump rod, said body having opposing faces spaced inwardly from the ends of said hub member, an integral flange arranged about the periphery of said body, a pair of cup members opposingly arranged on said body and having interlocking means thereon detachably associating the same with said body member, and retainer plates securing said cup members on said body member.

3. In a slush pump piston, in combination with a pump rod and cylinder liner, a hollow body member formed with a hub portion adapted to fit said pump rod, the said body member being cylindrical in form and having opposing faces transversely of its axis and spaced from the ends of said hub member, a peripheral flange formed about said body intermediate its said faces, a staggered arrangement of slots formed in each of said faces, a pair of identical pump rubbers arranged over said body and joining said flange, and having detachable interlocking association with the said slots, and retainer means removably securing said pump rubbers.

4. In a slush pump piston, in combination with a pump rod and cylinder liner, a body portion formed with a hub member conformable to said rod, the said hub member extending from each side of said body member providing seats for flexible cup members operating in said liner, a pair of identical cup members arranged in opposing relationship about said body portion and having detachable interlocking association therewith, and means retaining said cup members in position on said body member.
